[57] CLAIM

The ornamental design for a golf club chipping wedge with elongate handle, as shown and described.

DESCRIPTION

FIG. 1 is a front perspective view of a golf club chipping wedge with elongate handle showing my new design;

FIG. 2 is an left side elevation view of FIG. 2;

FIG. 3 is a right side elevation view of FIG. 2;

FIG. 4 is a bottom plan view of FIG. 2;

FIG. 5 is a blown up top plan view of FIG. 2;

FIG. 6 is a blown up broken away view of the face of the club;

FIG. 7 is a blown up bottom plan view of the club; and,

FIG. 8 is a blown up broken away view of the rear face of the club.

The broken line showing of the human figure and the ball in FIG. 1 is for illustrative purposes only and forms up part of the claimed design.
